FISH LURE

Ewell J. Harris, Rte. 3, P.O. Box 135A,
Adrian, Mich. 49221

Filed May 22, 1972, Ser. No. 255,939

Term of patent 14 years

Int. Cl. D22—05

U.S. Cl. D22—27

Fig. 2

Fig. 1

Fig. 3

Fig. 4

Fig. 5

FIG. 1 is a side view of a fish lure embodying the present invention shown upside down from its normal position;

FIG. 2 is a top plan view of the fish lure shown in FIG. 1;

FIG. 3 is a bottom view of the fish lure shown in FIG. 1;

FIG. 4 is a front view of the fish lure shown in FIG. 1; and

FIG. 5 is a rear end view of the fish lure shown in FIG. 1.

I claim:

The ornamental design for a fish lure, substantially as shown.
